CATHODE RAY PICTURE SCANNER

Rudolf Urtel, Berlin, Germany, assignor to Telefunken Gesellschaft für Drahtlose Telegraphie m. b. H., Berlin, Germany, a corporation of Germany

Application June 8, 1937, Serial No. 146,990
In Germany June 9, 1936

12 Claims. (Cl. 178—7.2)

This invention relates to cathode ray picture scanners and in particular, to method and means for compensating for disturbances in such tubes which result in irregular brightness distribution at the reproducer of the receiver.

In cathode ray picture scanners, even when the picture to be transmitted consists of a surface with uniform brightness and without any details, there can be noted an irregular distribution of the brightness at the receiver side, such as shown for instance in Fig. 1. This distribution of the brilliancy designated in the following as disturbance signal, occurs at the transmission of a tele-picture and is observed as additional blackening of the receiving image. It is possible to compensate this disturbance signal in that a compensation signal is produced artificially at the transmitter side which when added to, or subtracted from the output currents of the cathode ray scanner, causes at the receiver side just the disappearance of the said disturbance signal as shown, for example, in my copending application Serial No. 107,815, filed October 27, 1936, and entitled "Signalling circuit." But the value of the disturbance signal is dependent on the operating conditions of the cathode ray scanner, such as for instance on the average brightness of the image to be transmitted into distance. It follows therefrom that during the telecast it is not possible to use always the same compensation signal, but the apparatus furnishing the compensation signal must be subsequently adjusted with regard to the variations of the mean brightness, if importance is to be attached to an always exact compensation.

In order to avoid this disadvantage, in addition to the light for projecting the image, a diffuse beam of light rays having the same luminous density throughout its entire section impinges on the photosensitive surface of the scanner in accordance with the invention. At this additional diffuse irradiation the fluctuations of the total light current impinging on the scanner, are proportionately lower than without the said diffuse light. Consequently, the variation in the value of the disturbance signal is likewise smaller than if the time variation of the preliminary light impinging on the scanner has its cause solely in the variations of the average brightness. The slight residual variations in the value of the disturbance signal can furthermore be eliminated if the diffuse preliminary light is continuously varied in function of the average brightness, such that the total light current impinging on the cathode ray scanner remains constant as to time. In this case the effect of the average brightness upon the disturbance signal is entirely obviated, and hence, during the entire telecast the same setting of the apparatus furnishing the compensation signal

can be used without the disturbance signal appearing at the receiver side.

The invention will now be described in detail with reference to the drawing in which:

Fig. 1 shows diagrammatically the non-uniform distribution of illumination at the receiver due to "dark-spot" disturbances at the scanner;

Fig. 2 shows diagrammatically one embodiment of the invention in which diffused light of constant intensity is superimposed on the image illumination on the mosaic electrode;

Fig. 3 shows a modification of the embodiment shown in Fig. 2 wherein the intensity of the diffused light is controlled by the average value of the image illumination while;

Fig. 4 shows a modification of the embodiment shown in Figs. 2 and 3 wherein a different method and means of projecting the diffused illumination is provided.

In Fig. 2, item 10 represents the object to be telecast, 11 is an objective projecting an image of the object on a transparent screen surface 12, and 13 is a cathode ray scanner on whose photosensitive surface 14 the projection screen 12 is reproduced by means of a further objective 15. The entire projection surface 12 is illuminated by diffuse light across a dispersion lens 17 which light is furnished by the source 16 having constant brightness.

The photosensitive surface 14 of the scanner therefore is impinged by a luminous current composed of a constant component supplied by the lamp 16, and a varying component corresponding to the average brightness of the image of the object 10. The proportionate variations of the entire luminous current obviously are smaller than those of the average image brightness, and therefore, the variations of the disturbance signal are likewise smaller at unchanged setting of the apparatus furnishing the compensation signal, than in the hitherto customary operating mode in which the light source 16 was absent.

Fig. 3 shows a mode of construction in which the object 10 is reproduced by means of the objective 15, directly on the photosensitive surface 14 of the scanner 13. Between the objective 15 and the scanner 13, a reflecting arrangement, for instance an oblique glass plate 18 is inserted which may eventually be adapted as a semi-permeable mirror. Between the plate 18 and the lamp 16 again the dispersion lens 17 is provided. The lamp 16 is connected to an amplifier 19 controlled by the photocell 20 which as such determines the average image brightness.

The arrangement according to Fig. 3 operates in such manner that at an increase in the average image brightness, the luminous current impinging on the surface 14 across the objective 15, increases at first. But at the same time 60

also the current furnished by the photocell 20 and conducted to the amplifier 19 increases. This amplifier is so adapted that its output current and hence, the brightness of the lamp 16 5 become smaller so that less light arrives from the lamp 16 at the scanner across the reflecting device 18, than at a lower average image brightness. The characteristic of the amplifier 19 is now so set that the total luminous current 10 impinging on the surface 14 always remains at least approximately constant.

In Fig. 4 another mode of construction is shown inasmuch as it differs from that according to Fig. 3. The glass plate 18 of Fig. 3 is 15 replaced by a smaller mirror 21 covering up a small portion of the surface of the objective 15, and projecting the light of the tube 16 upon the total photosensitive surface 14 of the scanner.

The invention can be equally well applied to 20 the transmission of open air scenes or stage scenes as well as for the transmission of films, and in the latter case the application is especially simple when the films are projected by means of a projector equipped with optical compensation means.

What I claim is:

1. In a television system wherein is provided a cathode ray scanner equipped with a mosaic electrode, the method of improving the operation which comprises the steps of projecting light images of objects of varying light intensity to be transmitted upon the mosaic electrode, and simultaneously illuminating the mosaic electrode by a flooding light beam of substantially 30 uniform density over the entire mosaic area and of an intensity which varies inversely with increases in average brilliancy in the light image for maintaining the total illumination upon the mosaic at a predetermined substantially constant 35 value.

2. In a television system wherein is provided a cathode ray tube scanner equipped with a mosaic electrode, the method of improving the operation which comprises the steps of projecting a light image of an object upon the mosaic electrode, and simultaneously irradiating by a flooding light beam the entire mosaic area with diffused light having constant density of illumination.

3. In a television system wherein is provided a cathode ray tube scanner equipped with a mosaic electrode, the method of improving the operation which comprises the steps of projecting a light image of an object upon the mosaic electrode, and simultaneously superimposing by a flooding light beam upon the entire mosaic electrode area light of constant intensity and constant density.

4. In a television system wherein is provided a cathode ray tube scanner equipped with a mosaic electrode, the method of improving the operation which comprises the steps of projecting a light image of an object upon the mosaic electrode, simultaneously superimposing by a flooding light beam upon the entire mosaic electrode area light of constant intensity and constant density, and regulating the intensity of the flooding light beam in accordance with the average value of illumination of the light image.

5. In a television system wherein is provided a cathode ray tube scanner equipped with a mosaic electrode, the method of improving the operation which comprises the steps of projecting a light image of an object upon the mosaic electrode, simultaneously superimposing by a flood-

ing light beam upon the entire mosaic electrode area light of constant intensity and constant density, and regulating the intensity of the flooding light beam inversely proportional to the average light value of illumination of the light 5 image.

6. In a television system wherein is provided a cathode ray scanner equipped with a mosaic electrode, the method of improving the operation which comprises the steps of projecting a light image of an object upon the mosaic electrode, simultaneously superimposing by a flooding light beam upon the entire mosaic area diffused light of constant density, scanning the mosaic to produce distorted signals representative of the illumination of the combined image and diffused light, and transmitting the produced signals together with signals for compensating for the distortion.

7. A television system comprising a cathode 20 ray tube having a mosaic electrode, means for projecting light images of objects of varying light intensity to be transmitted upon the mosaic electrode, and optical means including a flooding light beam of uniform density projected over the 25 entire mosaic electrode area for simultaneously maintaining the total illumination upon the mosaic at a predetermined substantially constant value.

8. A television system comprising a cathode 30 ray tube having a mosaic electrode, means for projecting a light image of an object upon the mosaic electrode, and optical means including a flooding light beam for simultaneously irradiating the entire mosaic area with diffused light 35 having constant density of illumination.

9. A television system comprising a cathode ray tube having a mosaic electrode, means for projecting a light image of an object upon the mosaic electrode, and flooding light beam means 40 for simultaneously superimposing upon the mosaic electrode area light of constant intensity and constant density.

10. A television system comprising a cathode ray tube having a mosaic electrode, means for 45 projecting a light image of an object upon the mosaic electrode, flooding light beam means for simultaneously superimposing upon the entire mosaic electrode area light of constant intensity and constant density, and means for regulating 50 the intensity in accordance with the average value of illumination of the light image.

11. A television system comprising a cathode ray tube having a mosaic electrode, means for projecting a light image of an object upon the 55 mosaic electrode, flooding light beam means for simultaneously superimposing upon the entire mosaic electrode area light of constant intensity and constant density, and means for regulating 60 the intensity inversely proportional to the average light value of illumination of the light image.

12. A television system comprising a cathode ray tube having a mosaic electrode, means for projecting a light image of an object upon the mosaic electrode, flooding light beam means for 65 simultaneously superimposing upon the entire mosaic area diffused light of constant density, means for scanning the mosaic to produce distorted signals representative of the illumination of the combined image and diffused light, and means for transmitting the produced signals together with signals for compensating for the distortion.
